UNITED STATES PATENT OFFICE.

DAVID BASCH, OF NEW YORK, N. Y.

NETHER GARMENT.

SPECIFICATION forming part of Letters Patent No. 549,048, dated October 29, 1895.

Application filed May 3, 1895. Serial No. 548,026. (No specimens.)

To all whom it may concern:

Be it known that I, DAVID BASCH, a citizen of the United States, residing at New York, in the county and State of New York, have 5 invented new and useful Improvements in Nether Garments, of which the following is a specification.

This invention relates to nether garments, as trousers or knickerbockers; and it has for 10 its object to provide novel means for preventing the chafing, soreness, or irritation which is liable to occur, especially in such exercise or pursuits as riding a bicycle, a horse, or the like.

15 The invention consists in the features of construction hereinafter described and claimed, reference being had to the accompanying drawings, in which—

Figure 1 is a rear elevation of a nether garment. Fig. 2 is a section along $\alpha\alpha$, Fig. 1. Fig. 3 is a detail view of a pad. Fig. 4 shows a modification. Fig. 5 is a section along $\gamma\gamma$, Fig. 4.

In the drawings is shown a nether garment having a pneumatic pad or seat. This pneumatic pad comprises the transverse portion 1 and the lateral portions or wings 2. A filling or access tube 3 enables the pad to be inflated or emptied, as desired.

30 The apparel—such, for example, as a pair of trousers or knickerbockers—has its seat portion 4 provided with a flap-piece 5 to form a pocket, the pad 1, 2 being housed in this pocket. The tube 3, being secured along the 35 rear of apparel and extending to the waistband, can serve for the ready inflation or collapsing of the pad, and when the apparel is being worn this tube 3, extending along the rear, will not be in position to annoy or interfere with the wearer. The tube 3, as well known, should have a valve for closing the outlet when the pad is to be kept inflated.

The lateral portions 2 of the pad, extending about the crotch portion of the apparel, will 40 keep the inner faces of the thighs from chafing against one another or against a saddle or other object.

If it should not be desired to apply the pad

to an outer garment, a supporter 6, Figs. 4 and 5, in drawers or trunk form, can be provided with the pad, and this supporter 6 can be put on before the outer apparel is put in place. Such a supporter 6 may be found useful with such a garment as a lady's skirt; but of course the supporter is not limited to use 50 with a lady's skirt only. Neither is the application of the pad limited to use with trousers or knickerbockers, since it can be elsewhere applied—as, for example, in bloomers, jockeys' trousers, and other articles. 55

For jockeys, where at times for reducing the weight a light or thinly-padded saddle is employed, the improved wearing-apparel will be found very satisfactory, and it may even serve for comfortable riding without a saddle, or 60 bareback, as also with light or thinly padded saddles, which are preferred in warm weather for relieving the rider as well as the mount. 65

The tube 3, while shown extended along the back, can, if found convenient, be extended along to any other desired point, as at the side, the front, or the crotch, or in some cases—as, for example, in permanent inflation—the tube can be omitted altogether and a valve applied directly to the pad. 70

75 What I claim as new, and desire to secure by Letters Patent, is—

1. A nether garment, provided at its seat portion with a pneumatic pad comprising a transverse portion and two lateral depending wing-portions, all constructed to fit the crotch-portion of the garment, substantially as described.

2. A nether garment, provided at its seat portion with a flap to form a pocket and a pneumatic pad comprising a transverse portion and two lateral depending wing portions contained in said pocket, substantially as described and for the purpose set forth.

In testimony whereof I have hereunto set 90 my hand in the presence of two subscribing witnesses.

DAVID BASCH.
